[57] CLAIM

The ornamental design for a spout, as shown and described.

DESCRIPTION

FIG. 1 is a perspective view of a spout showing my new design;

FIG. 2 is a front elevational view thereof;

FIG. 3 is a right side elevational view thereof, the left elevational view being identical;

FIG. 4 is a rear elevational view thereof;

FIG. 5 is a top plan view thereof;

FIG. 6 is a bottom plan view thereof;

FIG. 7 is a perspective view of an alternate embodiment of the spout shown in FIG. 1 with the only difference residing in an extension of the traverse axis; all other sides being identical to that shown in FIGS. 2-6; and

FIG. 8 is a perspective view of a second alternate embodiment of the spout shown in FIG. 1, with the only difference residing in an extension of the traverse axis;
all other sides being identical to that shown in FIGS.
2-6.

Fig. 1.

Fig. 2.

Fig. 3.

Fig. 4.

Fig. 5.

Fig. 6.

Fig. 7.

Fig. 8.
